Patented Oct. 23, 1917.

UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

LOOM-PICKER.

1,244,122.

Specification of Letters Patent. Patented Oct. 23, 1917.

Application filed January 8, 1916. Serial No. 70,937.

To all whom it may concern:

Be it known that I, JONAS NORTHRUP, a citizen of the United States, residing at Hopedale, in the county of Worcester and 5 State of Massachusetts, have invented certain new and useful Improvements in Loom-Pickers; and I do hereby declare the following to be a full, clear, and exact description of the invention, such as will enable others 10 skilled in the art to which it appertains to make and use the same.

The present invention relates to an improvement in loom pickers.

In converting old, plain looms, during the 15 operation of which weft replenishment is effected by the operator, into automatic, weft replenishing looms, it is usually necessary, among other alterations, to enlarge the aperture in the shuttle race, in which 20 the picker-staff oscillates, in order that the ejected bobbin may fall therethrough.

The enlargement of the picker-staff slot for the passage of the ejected bobbin, in that type of looms in which the picker-staff 25 is pivoted on the rock shaft sustaining the lay swords, allows the picker, which is loosely engaged by the picker staff, to fall below the shuttle race and thereby be out of position to engage the shuttle. Hitherto, 30 no simple and efficient device has been produced permitting this particular type of plain loom to be converted into an automatic loom without first radically altering the shuttle box and associated parts.

35 The object of the present invention is, therefore, the production of a device by means of which plain looms of the pivoted picker-staff type may be converted into automatic looms with a minimum requirement 40 of alterations in the shuttle box and its associated parts. To the accomplishment of this object, the invention consists of the improved loom picker described in the following specification and particularly pointed 45 out in the appended claims.

In the accompanying drawings illustrating the preferred form of the present invention, Figure 1 is a front elevation of the left-hand end of a loom showing the parts 50 necessary to a disclosure of the invention; Fig. 2 is a plan of the parts shown in Fig. 1, and Figs. 3 and 4 are sectional views respectively, on the lines 3-3 and 4-4 of Fig. 2.

55 The loom to which the improved picker

is applied may be, in general, of any usual construction. In the particular type of loom illustrated in the drawings, the picker-staff, which is indicated at 5, is pivoted at 6 on a rock shaft 7 journaled in the usual manner in the loom frame 8. The pivotal mounting of the picker-staff on the rock shaft makes necessary a loose connection between the picker and the picker-staff in order that the usual longitudinal movement 65 may be imparted to the picker at each actuation of the picker-staff. Accordingly, the picker, which is indicated at 9, is provided with a hole which is large enough for the free accommodation of the upper end of 70 the picker-staff, so that, as the picker-staff oscillates on its pivot, the picker may reciprocate longitudinally on the shuttle race 10. The shuttle race 10 forms the upper surface of the lay 11, which is supported by 75 the lay sword 12 mounted on the rock shaft 7. To permit the upper end of the picker-staff to oscillate to communicate a reciprocatory motion to the picker, that part of the shuttle race located above the picker-staff is 80 provided with a longitudinally disposed slot 14. This picker-staff slot is but slightly wider than the picker-staff; consequently, the picker,—which is considerably wider than the picker-staff,—has sufficient bearing 85 surface on the shuttle race adjacent the picker-staff slot so that it may slide over the slot and properly pick the shuttle.

If it is desired to convert the plain loom into an automatic loom, it is necessary to enlarge that portion 15 of the picker-staff slot situated below the bobbin when the shuttle is boxed. This portion 15 of the picker-staff slot is that part through which the bobbin passes when it is ejected from the shuttle by the transerrer hammer of the weft replenishing mechanism. This enlargement of the picker-staff slot at the portion 15 is necessary because the original width thereof is not sufficient to allow the 100 free passage therethrough of the ejected bobbin. When the picker-staff slot has been thus enlarged for the accommodation of the ejected bobbin, it is found that the picker, as originally made, is not wide 105 enough to prevent its dropping through the enlarged slot. Now it is obvious that if a new picker were made of such width as to prevent its falling through the enlarged portion of the picker-staff slot, it would be 110

necessary to relocate the binder, because the binder occupies such position relatively to the picker, as originally made, that its inside wall terminates closely adjacent the 5 path of movement of the picker. The relocation of the binder to accommodate the widened picker would render it inoperative to perform its function of smothering the force of the shuttle as it enters the shuttle 10 box, and prevent its rebound therefrom. The proposition, then, resolves itself in evolving a device which will effectively prevent the displacement of the picker and allow it to perform its shuttle picking function 15 properly and, at the same time, keep the other parts of the shuttle box substantially unaltered.

In accordance with this proposition, the invention contemplates interposing a plate-like 20 device of low friction material between the picker and the shuttle race. Although the invention is not restricted to the use of any particular material for the purpose, experiment has demonstrated that rawhide 25 answers the requirements of the situation more satisfactorily than other materials. A thin plate-like strip of rawhide 16 is, therefore, interposed between the picker 9 and the shuttle race 10. The rawhide picker 30 plate 16 is oblong in outline, as shown in Fig. 2, is provided with an aperture for the reception of the upper end of the picker-staff, is of the same length as the picker, and is of sufficient width to enable it to pass over 35 the enlarged portion 15 of the picker-staff slot 14 without liability of the picker being projected therethrough. Inasmuch as the inner wall of the binder, indicated at 17, approaches very closely to the picker, as 40 hereinbefore described, it is necessary to cut a recess 18 in the lower inner corner of the binder contiguous to the shuttle race, as shown in Fig. 4, to permit the picker plate 16 to pass freely therethrough. This slight 45 recessing of the binder is the only alteration necessary to remove impediments to the reciprocation of the picker plate.

When an old loom of the pivoted picker-staff type has been converted into an auto-

matic loom, and the shuttle box has been 50 altered in the manner described, the interposition of the rawhide picker plate between the picker and the shuttle race permits the picker to perform its shuttle picking function in the same manner in which it was 55 performed before the conversion of the old loom as a plain loom into an automatic loom. The picker plate is comparatively thin, being of just sufficient thickness to properly support the weight of the picker, so that 60 it is not necessary to make any alterations in the height of the shuttle box. It is apparent, then, from the foregoing description, that by means of the present invention a plain loom of the pivoted picker-staff 65 type may be converted into an automatic loom with a minimum requirement of shuttle box alteration.

Having thus described a preferred form of the invention, what is claimed as new is:— 70

1. A loom having, in combination, a lay, a shuttle race, a shuttle box, a binder arranged to yieldingly engage the shuttle as it enters the shuttle box, a pivoted picker-staff, a picker loosely engaging the picker-staff, a picker-staff slot in the shuttle race having an enlarged portion of greater width than the picker for the passage therethrough of an ejected bobbin, and a low friction plate of greater width than the enlarged 80 portion of the slot interposed between the picker and the shuttle race.

2. A loom having, in combination, a lay, a shuttle race, a shuttle box, a pivoted picker-staff, a picker loosely engaging the 85 picker-staff, a binder having an inside wall closely adjacent to one side of the path of travel of the picker for yieldingly engaging the shuttle as it enters the shuttle box, a picker-staff slot having an enlarged portion 90 of greater width than the picker, a plate of greater width than the enlarged portion of the slot interposed between the picker and the shuttle race, and a recess formed in the inner wall of the binder for the free passage 95 of the part of the plate extending laterally beyond the picker.

JONAS NORTHROP.
